UNITED STATES PATENT OFFICE

OMAR E. CLARK, OF DENVER, COLORADO, ASSIGNOR TO GARDNER-DENVER COMPANY,
OF DENVER, COLORADO, A CORPORATION OF DELAWARE

ROTARY COMPRESSOR

Application filed April 16, 1928. Serial No. 270,447.

The present invention relates to air and gas compressors of the rotary type, and involving the fundamentals of the Gause-Conrady type of structure, in which a rotor is capable of 5 endwise play to provide adequate packings at the ends thereof and automatically take up wear.

The object is to provide a structure of a novel character that can be properly balanced 10 to eliminate vibration and is thoroughly lubricated, at the same time the air compressing portion is effectively sealed from the lubricant.

The preferred embodiment of the invention is illustrated in the accompanying drawings; wherein:

Figure 1 is a vertical longitudinal sectional view through the structure.

Figure 2 is a cross sectional view on the line 2—2 of Figure 1.

Figure 3 is a detail end view of the eccentric adjusting means.

Figure 4 is a sectional view on the line 4—4 of Figure 2.

Figure 5 is a sectional view on the line 5—5 of Figure 2.

In the disclosure, a casing is employed, comprising a peripheral wall 6, to which end heads 7 and 8 are secured by bolts 9. The 30 wall 6 and heads 8 are chambered, as illustrated at 10 and 11 to provide for the circulation of a cooling medium. The peripheral wall has an annular inset portion 12. This inset portion is spaced from the heads 7 and 35 8, and at the side adjacent to the head 7 is provided with a bearing surface 13. Secured to the opposite side of said inset portion by bolts 14 is an inwardly extending ring or abutment wall 15 that is spaced from the adjacent head 8. The casing provides an internal rotor chamber, of which the inner 40 face 16 of the inset portion 12 constitutes the outer wall.

A shaft 17 extends across the casing and 45 has roller bearings 18 in the heads 7 and 8.

This shaft is provided within the rotor casing with an integral and relatively small eccentric 19. On said eccentric is journaled a larger eccentric 20. Surrounding the central portion of this eccentric 20 is a wear sleeve 21, on which is journaled the hub 22 of a hollow rotor. This rotor includes said hub 22, a radial web 23 springing centrally from the hub, and a circular peripheral wall 24 that rolls on the surface 16 of the inset portion 12 of the annular wall 6. The web 23 is preferably braced by opposite ribs 25 and is perforated, as illustrated at 26 between said ribs, so as to afford free communication between the ends of the rotor. The rotor is 50 of the Gause-Conrady type, in that it is 55 slideable longitudinally of and on the shaft and is provided at one end with an enlarged terminal flange or head 27 that bears against the inner face of the inset abutment wall 15. At 60 its other end it is provided with an outstanding annular flange 28 that bears against the abutment face or wall 13 of the inset portion 12. These abutting faces, it will be understood, are carefully dressed so as to afford 65 as nearly as practicable air and liquid-tight joints. The rotor is permanently held in 70 said bearing engagement by means of a ring 29 that is pressed against the flange 28 by 75 springs 30 interposed between said ring and the adjacent head 7. The ring is held against rotation by dowel pins 31 carried by the heads 7 and slidably engaged in the ring.

The ends of the eccentric 20 are longitudinally split, as shown at 32 to form contractile 80 sleeves that will grip the eccentric 19 of the shaft 17, and surrounding said end portions are split collars 33 carrying counterweights 34 that are thus located on opposite sides of the hub 22 and are within the peripheral wall 85 24 of the rotor.

Contracting bolts 35, engaged in terminal ears 36, formed on said contractile collars 33, serve to not only draw the collars tightly 90 upon the terminal portions of the eccentric

20, but also contract said terminal portions on the eccentric 19 of the shaft 17, thereby holding all in fixed relation. The collars 33 are, however, preferably keyed, as illustrated at 37 (see Figure 3) to the eccentric 20.

5 One of the split collars 33, as shown in Figure 3, has a portion cut-away, as illustrated at 38, and an abutment pin 39 carried by the shaft 17, is located in this seat or socket formed by the cut-away portion. On opposite sides of this abutment pin are adjusting screws 40 threaded through the collar and abutted against opposite sides of the pin 39. These screws are held against accidental rotation by jamb nuts 41. It will thus be evident that by adjusting the screws 40, the cam 20 is turned with respect to the cam 19, thereby adjusting the rotor 24 toward and from the peripheral wall 6 of the casing.

20 By referring to Figures 1 and 2, it will be noted that the peripheral wall 24 serves to divide the rotor chamber into an outer compression chamber 41^a and an inner chamber 42, the latter constituting a reservoir for lubricant, and that these chambers are sealed against each other by the bearing of the head 27 of the rotor against the abutment wall 15 and the bearing of the flange 28 of the rotor against the abutment wall 13. Therefore 25 neither air or gas can pass from the chamber 41^a into the chamber 42, nor can lubricant pass from the chamber 42 into the compression chamber 41^a. Lubricant is supplied to the chamber 42 through a port 43 formed in the top of the cylinder wall 6 and closed by a detachable plug 44. This port 43 opens into the space between the head 8 and the abutment wall 15. This lubricant, it will be noted, has free access to all the internal parts 30 of the apparatus, and as the shaft 17 rotates, the counterweights 34 will serve to splash it about within the chamber 42. More than that, ports 45 open from said chamber 42 to the bearings 18, and the hub of the rotor has 35 a passageway 46 that opens to the bearing sleeve 21, said bearing sleeve in turn may have portage 47 to grooves 48 within the rear eccentric 20 and opening back into the chamber 42. The lubricant can be drained 40 through a drawoff opening 49 normally closed by a plug 50.

The compression chamber 41^a is supplied through a transverse series of ports 51 (see Figures 2 and 4) that open on one side of an 45 abutment 52 that extends across the chamber 41^a and bears against the peripheral wall 24 of the rotor. These inlet ports 51 communicate with a common intake chamber 53, across which is placed a screen 54. An outstanding 50 nipple 55 is internally threaded to receive a supply pipe if such is desired. On the opposite side of the abutment 52 is formed on the casing an outlet chamber 56 opening into the compression chamber 41^a through a series of ports 57 (see Figures 1 and 2). In

these ports 57 are located ring disk valves 58 placed in housings 59 and held in place by suitable pressure stems 60 that are borne upon by cap screws 61. An outlet port from the chamber 56 is shown at 62.

70 The abutment 52 may be of any desired character but as shown, consists of slidably overlapped plate sections 63, on which are placed bearing caps 64. These caps are pressed upon by coiled springs 65 located in chambers 66 and in turn borne upon by plug closures 67 threaded into the outer ends of the chambers 66.

75 With this structure, it will be evident that when the shaft 17 is rotated, the rotor will also be rotated and because of its eccentric mounting, its periphery will ride the inner face 16 of the peripheral wall. As a consequence, air taken in through the ports 51, will be compressed and delivered into the outlet chamber 56. Should wear take place between the peripheral wall 24 of the rotor and the surface 16, by adjusting the cam 20 with respect to the shaft 17 and its cam 19, this wear can be taken up. The end wear due to 80 the movement of the end surface 27 of the rotor against the abutment wall 15 and the corresponding movement of the flange 28 against the abutment surface 13, is automatically taken up as in the Gause-Conrady type 85 of apparatus, save that in the present structure, these bearings are always maintained by the springs 30, whose power is sufficient to overcome any outward or back pressure on the flange 28, due to the compression of the air or gas in the chamber 41^a. And in this 90 respect, it will be noted by reference to Figure 2, that the springs are utilized only on that portion of the flange which is subjected 95 to material outward pressure, and that they are located closer and closer together as they are located nearer and nearer to the outlet ports 57, so that the outward pressure is more evenly counterbalanced as it increases. Obviously this can also be obtained by using 100 springs of varying degrees of resistance.

105 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages 110 of the invention.

115 What I claim, is:

1. In a rotary compressor, the combination 120 with a casing having a rotor chamber, of a shaft in the chamber having an eccentric, a rotor having a hub mounted on the eccentric, said eccentric projecting beyond the opposite sides of the hub, and counterweights having hubs clamped to the projecting ends 125 130

- of the eccentric and located on opposite sides of the hub.
2. In a rotary compressor, the combination with a casing having a rotor chamber, of a shaft therein, an eccentric rotatably mounted on the shaft, an abutment carried by the shaft, adjusting bolts carried by the eccentric, and engaging the opposite sides of the abutment to hold the eccentric in different positions with respect to the shaft, and a rotor on the eccentric.
3. In a rotary compressor, the combination with a casing having a rotor chamber, of a shaft therein, an eccentric rotatably mounted on the shaft, a counterweight carried by the eccentric, means carried by the counterweight for adjusting the eccentric on the shaft and holding it in adjusted position therein, and a rotor mounted on the eccentric.
4. In a rotary compressor, the combination with a casing having a rotor chamber, of a shaft therein, an eccentric rotatably mounted on the shaft, a counterweight carried by the eccentric, an abutment carried by the shaft, adjusting and holding screws carried by the counterweight and engaging the abutment, and a rotor mounted on the eccentric.
5. In a rotary compressor, the combination with a casing having a rotor chamber, of a shaft therein, and having an eccentric, a second eccentric rotatably mounted on the first eccentric, a counterweight carried by the second eccentric, an abutment on the shaft, adjusting and holding devices carried by the counterweight and engaged with the abutment, and a rotor mounted on the second eccentric.
6. In a rotary compressor, the combination with a casing having a rotor chamber, of a shaft in the chamber, an eccentric journaled on the shaft and having a split sleeve, a counterweight having a contractile hub on the split sleeve of the eccentric, means for contracting the hub on the sleeve and the sleeve on the shaft, and a rotor mounted on the eccentric.
7. In a rotary compressor, the combination with a casing having a rotor chamber, of a shaft having an eccentric in the chamber, a second eccentric journaled on the first eccentric and having a split sleeve, a counterweight having a contractile hub on the split sleeve of the second eccentric, means for contracting the hub on the sleeve and the sleeve on the first eccentric, and a rotor mounted on the second eccentric.
8. In a rotary compressor, the combination with a casing having a rotor chamber, of a shaft having an eccentric in the chamber, a second eccentric journaled on the first eccentric and having a split sleeve, a counterweight having a contractile hub on the split sleeve of the second eccentric, means for contracting the hub on the sleeve and the sleeve on the first eccentric, an abutment project-
- ing from the shaft, adjusting and holding bolts on the counterweight, and engaged with the abutment, and a rotor mounted on the second eccentric.
9. In a rotary compressor, the combination with a casing having a rotor chamber, end heads closing the chamber, and abutment walls inside and spaced from the end heads, of a shaft journaled in the end heads, a hollow rotor eccentrically mounted on the shaft and having end portions rotatably bearing against the side faces of the abutment walls, said rotor having a peripheral wall dividing the rotor chamber into an outer compression chamber and an inner lubricant chamber and said rotatable portions closing the said inner and outer chambers against communication, and means whereby lubricant is supplied to the inner chamber.
10. In a rotary compressor, the combination with a casing having a rotor chamber, end heads closing the chamber, and abutment walls inside and spaced from the end heads, of a shaft journaled in the end heads, a hollow rotor eccentrically mounted on the shaft and having end portions rotatably bearing against the side faces of the abutment walls, said rotor having a peripheral wall dividing the rotor chamber into an outer compression chamber and an inner lubricant chamber and said rotatable portions closing the said inner and outer chambers against communication, and means whereby lubricant is supplied to the inner chamber, said chamber opening through the rotor to the spaces between the heads and the abutment walls and having access to the shaft bearing.
11. In a rotary compressor, the combination with a casing having a peripheral wall and end heads, of an outstanding abutment wall in the casing at one end and spaced from the head, an inset annular wall in the other end of the casing spaced from the other head, a shaft journaled in the heads, and a hollow rotor having a hub eccentrically journaled in the shaft and having an end abutting the inner face of the inset abutment wall and spaced from the adjacent head, said rotor having an outstanding flange at its other end abutting the outer face of the outstanding abutment wall and spaced from the adjacent head, a ring in the space and bearing against the flange, springs interposed between the adjacent head and ring, counterweights fixed to the shaft within the rotor, and means whereby lubricant can be supplied to the interior of the rotor, and to the spaces between the heads and abutment walls and to the bearings of the rotor hub and shaft.
12. In a rotary compressor, the combination with a casing having a rotor chamber, of a shaft therein, an eccentric rotatably mounted on the shaft, a counterweight, means for mounting the counterweight on the eccentric, said mounting means constitut-

ing means for securing the eccentric against rotation on the shaft, and a rotor on the eccentric operating in the rotor chamber.

13. In a rotary compressor, the combination with a casing having a rotor chamber, of a shaft therein, an eccentric rotatably mounted on the shaft and having a contractile portion, a counterweight having a contractile portion on the contractile portion of
10 the eccentric, means for contracting the last mentioned portion and thereby the first mentioned portion, and a rotor mounted on the eccentric and operating in the rotor chamber.

15 In testimony whereof, I affix my signature.
OMAR E. CLARK.
